PUMP ASSEMBLY

Knut E. Lundin, Los Angeles, Calif., assignor to
 Radial Pump and Compressor Company, Los
 Angeles, Calif.

Application April 19, 1940, Serial No. 330,518

5 Claims. (Cl. 103—6)

The present invention relates to pumping devices and particularly to an improved pump assembly adapted for pumping either air or water, or a combination of both.

It is an important object of the invention to provide in a device of the above character improved means for pumping either air or water alone or simultaneously. When operating in the latter fashion the device is particularly well adapted for pumping water from deep wells wherein the air from the air cylinders opens into a casing connected to the water cylinders below the level of the water in the well casing.

One object of the invention is to provide a novel and improved combined basal support and water conduit for a pumping assembly, said assembly being arranged to pump both air and water, such basal support being of a sturdy character and also affording a convenient means for quickly installing the pumping structure in its operative position.

Still another object relates to the provision of a combined pump assembly housing and fluid containing chambers, the walls of said chambers not only forming parts of the conduit system of the pump but also serving as cover members for the housing which may readily be removed therefrom and reattached whenever access to the interior of said housing is desired.

A yet further object is to provide, in combination with other features of the invention, a pump cylinder structure wherein the residual air space remaining after the piston has advanced to the limit of the expulsion stroke is reduced to a minimum, this feature being a result of constructing and positioning the valves in an improved manner.

It is also an object of the invention to provide, along with other improved features, a pumping assembly which may be mounted with either of two opposite sides directed upwardly, thereby facilitating connecting therewith the driving means.

It is also an object of importance to improve upon and simplify the construction set forth in my Power transmitting device, patented June 13, 1933, No. 1,914,141.

With the foregoing and other objects in view, the invention resides in the novel arrangement and combination of parts and in the details of construction hereinafter described and claimed, it being understood that changes in the precise embodiment of the invention herein disclosed may be made within the scope of the subject

matter claimed without departing from the spirit of the invention.

Apparatus embodying features of my invention is shown on the accompanying drawings, forming a part of this application, wherein,

Fig. 1 is a plan view of the improved apparatus;

Fig. 2 is a view similar to Fig. 1 with certain upper portions removed in order to show interior construction;

Fig. 3 is a section taken on line 3—3 of Fig. 1, except that some parts are shown in elevation;

Fig. 4 is an enlarged vertical mid section of one of the intake valves; and,

Fig. 5 is an enlarged mid section of one of the discharge valves.

Referring in detail to the drawings, and at first more particularly to Fig. 1, a pumping assembly 10 is shown supported by a horizontally extending basal conduit 11, which is approximately C-shaped, said assembly communicating with said conduit through the same pipe sections 12, 13 and 14 whereby it is supported superjacent thereto.

In the illustrated embodiment of the invention, said pumping assembly is contained within a hexagonal housing frame 15 and comprises a series of six pumping cylinders, three of which, 20, 21 and 22, are shown for pumping air and the alternating other three, 23, 24 and 25, are shown for pumping water. Said six cylinders occupy substantially the same horizontal plane and are circumferentially arranged in relation to the circular conduit 11 with their axes radially positioned in relation to the center of the pumping assembly. Said cylinders and their pistons 30 and adjacent parts (except the master rod 29) are all shown as being of identical construction and therefore are all lettered in the same manner.

Five of said pistons each have a rod 31 which is rockably connected by a pin 32 to a gyroscopic split crosshead disk 33.

Said crosshead disk is shown mounted upon and driven by an integral crankshaft structure comprising a central shaft section 34 having eccentrically related to it a circular lower enlargement 39 furnished below with a short shaft section 40; there being above said crosshead disk another circular enlargement 35 which has upwardly extending from it a short shaft section 36, the shaft sections 36 and 40 being in alignment with each other. The shaft section 36 is journaled in a bearing 36b which is of an inverted cup shape and which is fitted into a tubu-

lar cross wall 37 of a top reservoir 38. Likewise the lower shaft section 40 has a cup-shaped bearing 40b which is contained in a circular cross wall 41 of a lower reservoir 42. A circumferential flange or bead 35a of the crankshaft enlargement 35 is shown as being of the same diameter as the lower shaft enlargement 39, but above said portion 35a the part 35 is shown machined down to a less diameter. Said flange 35a affords a support for the gear 35b which is mounted upon the shaft enlargement 35 and is keyed thereto at 35k. With the gear 35b meshes a driving pinion 45 carried by the lower end of a shaft 46, said shaft having fixed to its upper end a pulley 47 driven by the belt 48.

A description will now be given of the structural details found in each of the six identical piston and piston cylinder units.

Using for an example the piston unit which has the cylinder 20 (left side of Fig. 3), said cylinder has flanged portions 20f near housing frame 15, said frame having suitable circular openings into which are fitted the basal portions of this and all the other piston cylinders.

The rod 29 of the piston being described, as has already been mentioned, is not pivotally, but rigidly connected to the crosshead disk 33. It is the master guide-connecting-rod which maintains the proper eccentricity of the remaining pins 32 with respect to their center of gyration. Rivets 29a connect said rod 29 to said disk 33.

Each of the piston rods 31, like the master rod 29, is swingably connected with its piston by means of a pin or small shaft 49 which extends diametrically of the inner portion of the head of the piston.

To the outer end of each piston cylinder is secured a chambered piston cylinder cap 50 furnished on its inner face with an annular flange 51 which fits into the outer end of the piston cylinder.

Each cap 50 contains an upper chamber 55 and a lower chamber 56, the upper chamber in the left hand portion of Fig. 3 being an air intake chamber, the chamber below it an air exhaust chamber, while at the right hand side of the assembly water is handled and the two chambers are reversely positioned as to intake and exhaust. This is due to the fact that the air and water handling pistons alternate with each other as can be seen from the fact that alternate cylinders of Figs. 1 and 2 have air filters 57. As shown in Fig. 3, each of said filters is of a tubular character, having an externally threaded shank 57s which is screwed into a passage which leads into the chamber 55.

In Fig. 4 is shown in detail the structure of the intake valve 58 which in the upper left hand portion of Fig. 3 permits air entrained through the air filter 57 into chamber 55 to flow only in a direction for discharging it from said chamber 55 into the piston cylinder; the same kind of valve structure 58 in the lower right hand portion of Fig. 3 permitting water entering chamber 56 from pipe 12 to flow only in a direction to be entrained from said chamber into the piston cylinder.

Each valve 58 seats upon the beveled seat of a valve seat member 58a which is screwed into the passage 59 to which its relates. Valve seat member 58a has an annular flange 58b around the valve seat which is countersunk flush with the inner face of the cap 50. Diametrically across the member 58a extends a web 60 through which works the headed stem 61 of the valve 58, a

spring 62, occupying a seat 63, tending to move the valve to its seated position.

In Fig. 5 is shown in detail the structure of an exhaust valve 65 which, in the lower left hand portion of Fig. 3 permits air to flow only in a direction for discharging it from the piston cylinder into the chamber 56 and thence through a conduit 75 into the lower reservoir 42; and this valve structure in the upper right hand portion of Fig. 3 permits water to flow only in a direction for discharging it from the piston cylinder into the chamber 55, and thence through conduit 76 into the upper top reservoir 38.

From the top reservoir 38 the water flows through conduit 77 to a place of use; a conduit 78 conducting the air from the lower reservoir 42 to a place of use.

Each valve 65 seats upon the beveled seat of a valve seat member 66 which is screwed into the passage 67 to which it relates. Diametrically across said member 66 extends a web 68 through which works the headed stem 69 of the valve 65. At its opposite side said valve has a central projection 70 around which is coiled one end portion of a compression spring 72 which spans the chamber 56 (or 55) and tends to seat the valve.

Valve seat member 66 has an annular flange 66a around the valve seat which is countersunk flush with the inner face of the cap 50.

Water from an available source, as for example from a well, is entrained by certain of the cylinders in the pump assembly 10 through a pipe 11f into the C-shaped pipe 11. From said pipe 11 the water is conveyed through the three upstanding pipes 12, 13, and 14 to the chambers 58 of the cap 50 of the respective cylinders 23, 24, and 25. From said caps 50, the pistons 30 on their suction stroke open the intake valves 58 by overcoming the resistance of springs 62 and draw the water into each said respective cylinder. On the exhaust stroke of each piston of said respective cylinders the valve 65 is opened by overcoming the resistance of the spring 72, and water is forced through said valve into the chambers 55 of the respective cylinders, thence through conduits 76 into the reservoir 38, and from said reservoir into conduit 77 to a place of use.

Simultaneously the pistons in the air cylinders 20, 21, and 22, working in alternation with the water cylinders, entrain air through the filters 57 into the chambers 55, past the valves 58, into the respective cylinders and then force it out through conduits 75 into the air reservoir 42, the previously described mechanism, similar to that used in the operation of pumping water just outlined.

The air from the reservoir may be utilized to aid in elevating the water from a well supplying water to the pipe 11f, in a manner which is well known.

Power for operating the pistons connected to the cross head 33 is supplied by the crank shaft through the medium of the gearing 35b and 45 operated by means of the shaft 46, the driving belt 48 and the pulley 47.

On the exhaust strokes of each piston the face of the piston adjacent the cap 50 is caused to move within a working clearance of the inner face of the cap in which the valves 58 and 65 are countersunk in order that no air pockets may exist which would tend to decrease the efficiency of the machine.

What is claimed is:

1. In a pumping assembly, an upper reservoir, a lower reservoir, said reservoirs being in a ver-

tically spaced relation to each other, a polygonal housing frame having an upper end attached to and closed by said upper reservoir and a lower end attached to and closed by said lower reservoir, said housing frame having peripheral openings, a plurality of pumping cylinders radially disposed in relation to the center of said frame with open inner ends fitted into said openings, caps closing the outer ends of said cylinders, each of said caps being provided with an upper chamber and with a lower chamber, pistons operating in said cylinders, valves in each of said caps permitting fluid to be entrained from one of said chambers into the piston cylinder closed by such cap and thence discharged from said cylinder into the other of said chambers, a common driving means for said pistons located within the aforesaid housing frame, and conduit means affording communication between certain of said chambers and said upper reservoir and the remainder of said chambers and said lower reservoir.

2. In a pumping assembly, an upper reservoir, a lower reservoir, said reservoirs being in a vertically spaced relation to each other, a polygonal housing frame having an upper end attached to and closed by said upper reservoir and a lower end attached to and closed by said lower reservoir, said housing frame having peripheral openings, a plurality of pumping cylinders radially disposed in relation to the center of said frame with open inner ends fitted into said openings, caps closing the outer ends of said cylinders, pistons operating in said cylinders, a common driving means for said pistons located within the aforesaid housing frame, and valve controlled conduit means through which fluid is forced by alternate said pistons respectively to said upper and lower reservoirs, said reservoirs forming a part of said conduit means.

3. In a pumping assembly, an upper reservoir, a lower reservoir, each of said reservoirs having extending through it an annular cross-wall, a housing frame having an upper end attached to and closed by said upper reservoir and a lower end attached to and closed by said lower reservoir thereby maintaining said annular cross walls in alinement with each other, a crank shaft having end portions journalled in said annular cross walls, pumping cylinders arranged in said housing frame radially with respect to said annular cross

walls, caps closing the outer ends of said cylinders, pistons operating in said cylinders, said pistons having rods operatively connected with said crank shaft, and a valve controlled conduit system to which said cylinders are operatively related, said reservoirs forming a part of said conduit system connecting certain of said cylinders to said upper reservoir and the remainder of said cylinders to said lower reservoir.

4. In a pumping assembly, a closed-in horizontally positioned reservoir having a vertical dimension relatively small in relation to its horizontal dimensions, said reservoir having extending vertically through its interior an annular cross wall, the space within said cross wall being open at the lower side of the tank, a housing of which said reservoir forms a top cover member, a lower bearing within said housing in a downwardly spaced relation to said cross wall, an upper bearing within said cross wall, a pump structure within said housing comprising pistons operated by a crank shaft having end portions journalled in said bearings, and conduits operatively related to said reservoir and pump structure.

5. In a pumping assembly, an upper reservoir, a lower reservoir, each of said reservoirs having extending through it an annular cross wall, a housing frame having an upper end attached to and closed by said lower reservoir thereby maintaining said annular cross walls in alinement with each other, a crank shaft having end portions journalled in said annular cross walls, pumping cylinders arranged in said housing radially with respect to said annular cross walls, caps closing the outer ends of said cylinders, pistons operating in said cylinders, said pistons having rods operatively connected to said crank shaft, and a valve controlled conduit system to which said cylinders are operatively related, said reservoirs forming a part of said conduit system, said conduit system comprising two divisions, one of which is open to the atmosphere and is arranged to force air through one of said reservoirs, and the other of which is arranged to force water through the other of said reservoirs, alternate said cylinders being in communication with the portion of said conduit system which conducts air, and the intervening cylinders being in communication with the portion of said conduit system which conducts water.

KNUT E. LUNDIN.
